UNITED STATES PATENT OFFICE.

GEORGE W. COLLIN, OF BRIDGEPORT, CONNECTICUT, ASSIGNOR TO THE COLLIN VALVE COMPANY, OF PORTLAND, MAINE, A CORPORATION OF MAINE.

FLUSHER-VALVE.

1,027,819.

Specification of Letters Patent. Patented May 28, 1912.

Application filed September 23, 1908. Serial No. 454,423.

To all whom it may concern:

Be it known that I, GEORGE W. COLLIN, a citizen of the United States, and resident of Bridgeport, in the county of Fairfield and State of Connecticut, have invented certain new and useful Improvements in Flusher-Valves, of which the following is a specification.

This invention relates to a simple form of flushing valve for use upon water closets, wash bowls, and similar places for drawing desired quantities of water, and whereby the flow of water will be automatically cut off when the valve handle is released by the attendant.

It is the purpose of my device to provide a practical and inexpensive form of valve that is adapted to be used as a closet flusher when connected intermediate of a closet bowl and the service pipe, or which may be produced in the form of a basin cock for supplying water to a wash basin, or in fact one which may be employed in numerous other places where it may be desired to manually draw quantities of water and have the same shut off automatically when the valve is released; to accomplish the above results without the use of springs or packings, which elements frequently wear out and cause trouble, and finally to design the valve in such a way that the same can readily be disassembled for cleaning or repairs.

With the above and other minor objects in view my invention resides and consists in the novel construction and arrangement of parts shown upon the accompanying two sheets of drawings forming a part of this specification, upon which similar characters of reference denote like or corresponding parts throughout the several figures and of which;

Figure 1, shows a central vertical longitudinal section of my improved flusher valve complete, and in a closed position. Fig. 2, is also a central vertical longitudinal section but taken at a right angle to Fig. 1. Fig. 3, is a plan view of the valve shown in Figs. 1 and 2. Fig. 4, is a detached plan view of the handle used on the valve. Fig. 5, is a plan view of a modified form of my invention carried out in the form of a basin cock, and Fig. 6, is a central vertical longitudinal section of the basin cock shown in Fig. 5, and more clearly showing the application of my invention.

Commercially speaking the two forms of my invention are called by different trade names since in design they have been shaped to better meet the uses to which they are put, yet in construction they differ principally in the shape of the casing and the relative location of the water inlet and outlet.

Figs. 1 to 4 inclusive of the drawing show the form of my invention to be used as a closet flusher and referring thereto in detail 10 indicates the casing which is formed of one piece being cored, bored and finished, to produce the several compartments, passages, inlet and outlet. The casing is further provided with a threaded hub 11 for attachment to a water service pipe, and through which hub an inlet 12 is formed to admit the water through the valve. 13 represents the piston chamber, and 14 a screw plug in upper end for inclosing the chamber in a manner to allow the removal of the piston 15 mounted therein. The piston carries a stem 16 to which the main valve 17 is secured, the same being provided with guide ribs 18 that engage the sides of the lower port 19 leading from the said piston chamber. The upper inner edge of the port 19 is beveled as shown to snugly receive the under beveled side of the valve 17. Beneath the said port 19 and valve 17 is the outlet 20 which as shown may be threaded for attachment to a closet bowl. Through the central portion of the inner end of the inlet 12 is a vertically disposed rib 21 that is arranged parallel with the piston stem, which I will term a splitter since it serves to divide and distribute the water evenly against the face of the piston valve and all sides of the stem. The cylindrical inlet 12 is provided with an annular groove 22 which is covered by a cylindrical screen 23, which serves to prevent dirt from entering the by pass and getting under the valves, and is of such a shape as to be cleaned with each direct flow of water therethrough. Leading from the said groove 22 is a by pass 24 having a beveled valve seat 25 therein adapted to receive the tapered end of a needle valve 26 for regulating the amount of water to pass through said valve and adjustably mounted in sleeve 27 threadably secured in the casing, the by pass 24 has its outlet into the upper portion of the piston chamber, above the piston, and serves to admit water thereinto from the inlet to 110.

establish and maintain a pressure upon the top of piston in a manner to hold the valve 17 down upon its seat, to prevent any leakage of water through the port 19.

- 5 A port 28 leads from the upper portion of the piston chamber, and communicates with the outlet 20 and is provided with a valve seat 29. A bore 30 is arranged to intersect this port as shown, and comprises 10 a large upper portion and a smaller lower portion forming an annular seat 31 therein. A plug valve 32 is slidably mounted to snugly fit both of said bores and is provided with finished shoulders to engage both the 15 seats 29 and 31, the former to control the flow of water from the piston chamber and the latter to prevent any leakage of water therefrom. This plug is provided with a series of annular grooves 33 in its periphery 20 to form water packings to prevent the water from leaking up around the plug and as a provision for such leakage as may get past said grooves, I provide a drain in the plug which comprises lateral holes 34 that 25 extend in from the periphery of the plug to take any water that may get past the lower water packing grooves, which holes intersect a central longitudinal hole 35 that has its outlet at the lower end of plug and into 30 the open end of port 28 and to the outlet. The plug 32 is further provided with a reduced neck 36 in its upper portion to form shoulders intermediate of which are seated the two members of the divided end 37 of 35 an operating lever 38 fulcrumed to a pin 39 secured to the casing. The weight of this lever upon the plug causes it to normally rest in a closed position as seen in Fig. 1, but the plug may be manually raised and 40 the lower valve 29 opened by lifting up on the free end of the handle as will be obvious and in a manner that will insure said parts again dropping to their lowered position, when released. From the foregoing 45 it will be seen that by reason of the divided end 37 of the handle 38 straddling the reduced cylindrical neck portion of the plug the latter may readily be turned with a suitable screw driver in a manner to grind 50 or regrind both of the valves to their seats 29 and 31 without disconnecting any of the parts.

Referring to Figs. 5 and 6, it will be seen that it is only necessary to change the shape 55 and proportions of a few of the parts in order to adapt my invention to use as a basin cock the casing 40 of which is of a somewhat different design than what would be used for a flusher. The valve for the 60 outlet port 19 is provided with a packing 41, attached to the valve by means of a screw 42 after the manner of an ordinary water faucet. The combined length of the piston and valve is much shorter in this 65 form than when used in the flusher valve

shown upon the other sheet. This form of valve is furthermore simplified somewhat though otherwise is substantially like the flusher and accordingly similar reference numerals are used to denote like parts.

From the foregoing construction it will be seen that the operation of either form of the device would be as follows:—The valve being connected up with a water supply (not shown) water is admitted to the intermediate and upper part of piston chamber in a manner to hold the valve shut against leaking. Should it be desirable at any time to draw water through the valve it would only be necessary to raise the outer end of 70 the operating lever 38, which in turn raises the plug 32 from the seat 29 to allow an escape of water from the upper chamber of casing through the port 28, which action releases the pressure upon top sides of piston thus causing the pressure beneath to raise said piston and its valve, opening the main passage through the valve and allowing a direct flow of water through the screen and port 19. The instant the handle 75 is released and allowed to drop, the plug valve again closes the port leading from the upper chamber causing the main water pressure to again build up through the by-pass 80 24 before mentioned.

Having thus described my invention what I claim and desire to secure by Letters Patent is:—

1. The combination of a casing having an inlet and an outlet communicating through a port, a valve for opening and closing the port, a differential area piston connected with the valve for actuating the same, a cylinder within the casing in which the piston reciprocates, an inlet passage through which liquid passes from the inlet to the cylinder to exert a greater pressure on the side of the piston of larger area than does the inlet pressure exert on the side of smaller area to normally hold the valve seated, a drain passage leading from the cylinder to permit liquid to flow out of the latter faster than it enters through the inlet passage whereby the inlet pressure acting on the side of the piston of smaller area moves the piston and opens the valve a chamber in the wall of the casing communicating with the drain passage and having an opening in its side, a handle extending into said opening and fulcrumed in the casing, 100 and a drain valve in the chamber for opening and closing said passage, said drain valve having spaced annular shoulders between which the handle engages to impart movement to the valve and whereby the handle forms the sole retaining means therefor, said shoulders permitting the valve to be turned for grinding its seating portion.

2. In a device of the class described, the combination of a casing having a drain pas- 105

sage, a vertical chamber communicating with the passage, a seat at the juncture of the chamber and passage, a plug valve fitting slidably and movable vertically in the chamber and normally engaging the seat by gravity, said valve having circumferential liquid packing grooves and a conduit for conducting off liquid escaping past the grooves, spaced shoulders on the valve, and 10 an operating handle having one end extending into and pivoted in the casing and dis-

posed between the shoulders of the valve whereby the handle normally retains the valve in place and seated.

Signed at Bridgeport in the county of 15
Fairfield and State of Connecticut this 19th
day of September, A. D. 1908.

GEORGE W. COLLIN.
